UNITED STATES PATENT OFFICE.

JOHN VAN VLECK, OF NEW YORK, N. Y., ASSIGNOR TO LEWIS B. STILLWELL, OF LAKEWOOD, NEW JERSEY.

FURNACE-GRAVE.

1,163,288.

Specification of Letters Patent.

Patented Dec. 7, 1915.

Application filed March 13, 1915. Serial No. 15,205.

To all whom it may concern:

Be it known that I, JOHN VAN VLECK, a citizen of the United States, residing at New York, county and State of New York, 5 have invented certain new and useful Improvements in Furnace-Grates, of which the following is a full, clear, and exact description.

This invention relates to furnace grates, 10 especially grates of the traveling belt type, and its object is to improve the same in various particulars.

A further object is to provide an improved system of air supply, whereby the 15 delivery of air to the burning fuel can be easily and effectively controlled.

To these and other ends the invention consists in the novel features of construction and combinations of elements hereinafter 20 described.

One of the various forms in which the invention can be embodied is illustrated in the accompanying drawings, in which—

Figure 1 is a vertical longitudinal section 25 taken at about the center of the furnace, showing the traveling grate, the upper air-chambers or compartments between the upper and lower reaches of the grate, and the lower air-chamber below the lower 30 reach. Figs. 2 and 3 are cross sections (on a larger scale) taken substantially on the planes indicated by the lines 2—2 and 3—3 of Fig. 1. Fig. 4 is a plan view of a grate “top” or top-plate of the preferred type, 35 and Fig. 5 is a side view of the same. Fig. 6 is a detail front view, partly in vertical section, of one of the grate carrier-bars with several top-plates thereon. Figs. 7 and 8 are detail cross sections on line 7—7 and 40 8—8, respectively, of Fig. 6.

Referring first to Figs. 1 and 2, 10 designates the fire or grate-chamber, having an arched roof 11, and at its front a mouth 12 for the introduction of fuel. Any suitable 15 fuel-feeding and regulating apparatus can be used, preferably that described in my co-pending application filed February 20th, Ser. No. 9,482. The traveling grate 13, of the belt type, moves from front to rear 50 (from left to right in Fig. 1) over two outer or front sprockets 14 on a transverse shaft 14^a and two rear or inner sprockets 15 on a transverse shaft 15^b, the outer sprockets being, in the present instance the larger. 55 Either or both pairs of sprockets can be

driven by any suitable mechanism, not shown. The upper reach of the grate is preferably inclined downwardly and rearwardly, and the two reaches are supported at the sides, to prevent sagging, by upper 60 and lower angle-iron rails 16, 17. Between the two reaches is an upper air-chamber 18 divided by a vertical transverse wall 19 into front and rear air-compartments 20, 21, respectively, receiving air, through lateral 65 openings 22, 23, from a lower air-chamber 24 which in turn receives air from a fan or blower (not shown) by way of an air-duct or conduit 25. A butterfly valve 26 in the mouth of the lower chamber regulates the 70 supply of air to the latter, while the supply to the front air-compartment 20 is regulated by butterfly valves 27 in the ducts leading upwardly from the sides of the lower chamber. The last-named valves are connected 75 by a reach-rod 28 so as to operate in unison. Any suitable means, not shown, can be provided for the manual operation or control of the valves 26, 27.

Below and at the rear of the upper reach 80 of the traveling grate 13 is an inner air-compartment 29, having a front wall 29^a. The bottom is formed by a lower stationary grid 30, and an upper movable grid so that by shifting the latter the supply of air to 85 the chamber, and hence to the fire on the rear end of the grate, can be accurately regulated. Preferably the movable grid is made in a plurality of independently adjustable parts or sections; as for example three, a 90 wide central section 31 and two narrower lateral sections 32, by which the more air per unit grate-area can be delivered to the center than to the sides of the grate, or vice versa, the three sections being separated by 95 longitudinal walls or partitions 29^b which divide the chamber into three separate cells. To shift the center section, it is provided with lugs 33, connected by rods 34 to arms 35 on a transverse rock shaft 36 in front of the chamber 29,—only one rod and one arm being shown. The left grid-section (Fig. 3) is similarly connected to an arm 37, Fig. 1, on the transverse shaft 38, and a like arm (not shown) is provided on the same shaft to operate the right-hand section. I have not considered it necessary to illustrate any particular means for rocking the shafts 36 and 38. It is to be understood that the invention, in respect to the grid-damper fea- 100 105 110

ture just described, is by no means limited to the location shown, that is, at the extreme inner end of the grate, nor to any particular size of damper.

- 5 To diminish leakage of air from the upper air-chamber to the outside and from one air-compartment to another, the transverse walls are provided at their tops with transverse plates 39 parallel with and close to the underside of the upper reach of the grate. The front and rear edges of these plates are bent downwardly, as shown, to avoid all possibility of interference with moving parts of the grate.
- 15 The top of the grate can be formed of long and narrow bars of the so-called "piano-key" type, but I prefer to use plates of the kind shown at 40 in Figs. 4, 5 and 6. These are castings provided with suitable air-openings, and at the sides are formed with depending fins or flanges 41 for attachment to the grate-top carrier bars as hereafter described. On one side of each plate at or near the top is a rib 42 and on the other side near or at the bottom is a similar rib 43, so that when a series of the top-plates or grate-tops are arranged side by side on the carrier bars the ribs will overlap each other at the sides, so as to prevent leakage of fuel thereat, and still be spaced far enough apart to prevent jamming as the grate passes the sprockets and to minimize crowding due to growth or expansion of the plates by heat. For a similar purpose the ends of the grate-tops overlap as shown in Fig. 1.

The hollow grate-top carrier-bars 44 (Figs. 6 and 7) are double-walled castings having front and rear walls, strengthened by longitudinal fins or flanges and connected by spaced transverse webs 46. The ends of the bars surround the grate-chains 47 and are pivotally attached to the links thereof as clearly shown in Figs. 2 and 6, wherein it is seen that the bar is connected to the chain 47 by a depending member 44^a fixed at its upper end to the bar and at its lower end loosely embracing the pivot 47^a of the chain. Directly above the walls or partitions 29^b, which, it will be remembered, divide the inner air-compartment into three cells, the carrier-bars are provided with forwardly and rearwardly extending fins or webs 48, Figs. 6 and 7, to cooperate with said partitions to diminish air-leakage from one cell to another.

At intervals along the sides at the top the carrier-bars 44 are equipped with front and rear lugs 49 for engagement with undercut notches or recesses in the grate-top webs or fins 41, as clearly shown in Figs. 1 and 7, permitting the grate-tops or plates to be removed from the carrier-bars by shifting them laterally until disengaged from the carrier-bar lugs. To hold the top plates against lateral displacement spacing pieces

50, (Fig. 6), are provided, bolted or otherwise removably fastened to the faces of the carrier bars between the depending fins 41. These spacing pieces or strips are important features of the invention, as they effectively prevent crowding of the grate-tops together at some point on the carrier bar, thereby opening up gaps at other points which may permit an objectionable leakage of fuel. The ends of the spacing plates are beveled at the top, as shown, to avoid interference with the carrier-bar lugs 49.

The grate-top plates, at the ends of the carrier-bars 44, are somewhat different from the intermediate plates, and the carrier-bars at such points are modified correspondingly. These end-plates are provided at their inner sides with depending fins 52, notched or recessed to straddle the carrier bar but are not interlocked therewith as are the other plates, while at their outer sides the fins are omitted and the bodies of the plates simply rest on the carrier-bars. Each end plate is held in place by a bolt 53, extending loosely through an aperture in the plate and an opening in the bar. Between the bottom of the bar and the nut on the bolt is a spring, preferably in the form of a spring washer, as 55. This mode of attachment gives the end-plate a certain resiliency or yield, the bolt rocking outwardly on the carrier-bar in response to pressure that may develop from lateral expansion or crowding of intermediate plates, thus preventing breakage. When spacing devices, as 50, are used with the intermediate plates, bodily displacement of the latter does not occur, and excessive pressure or stress on the end-plates is less likely, but if the spacing devices are omitted, as may happen by oversight or inadvertence in making repairs, the yielding connection of the end-plates to the carrier-bars affords a wide margin of safety against the inconvenience and loss that might result from breakage due to the use of a rigid connection.

It is to be understood that the invention is not limited to the specific construction herein illustrated and described, but can be embodied in other forms without departure from its spirit.

I claim:

1. In a traveling grate, the combination of a plurality of transverse carrier bars flexibly connected at their ends to form an endless belt, and a plurality of grate-tops removably mounted on the carrier bars, having their upper surfaces flush with each other and having their side edges provided with overlapping longitudinal flanges.
2. In a traveling grate, in combination, a transverse carrier-bar, a series of grate-tops arranged side by side on the carrier-bar and provided at their sides with overlapping ribs, and means for detachably securing the grate-tops to the carrier bar.

3. In a traveling grate, a perforated grate-top plate substantially rectangular in plan, provided with depending webs or fins at its sides having undercut recesses providing undercut front and rear lugs, and provided at its sides with outwardly extending ribs to overlap similar ribs on the adjacent plates when a series of such plates are arranged side by side in the grate.
4. In a traveling grate, the combination of a transverse carrier-bar, a series of intermediate grate-top plates arranged side by side on the carrier bar, an end-plate on the carrier-bar at the end of the series of intermediate plates; and means for securing the end-plates on the carrier-bar, comprising a device connected loosely at its lower end to the carrier-bar and extending upwardly into loose connection with the end-plate, and spring means yieldingly opposing outward rocking movement of the said upwardly extending device under pressure exerted laterally on the end-plate by the intermediate plates.
5. In a traveling grate, in combination, a transverse carrier-bar, a series of grate-top plates arranged side by side on the carrier-bar, laterally removable end-plates on the carrier-bar at the end of said series, and means for fastening the end-plates to the carrier bar, comprising vertical bolts loosely connected at the top to the end plates and at the bottom to the carrier-bar and yielding devices between the bolts and the carrier-bar, to permit lateral rocking movement of the bolts under pressure on the end plates.
6. In a traveling grate, a hollow transverse carrier bar comprising vertical front and rear walls spaced apart, forwardly extending lugs on the front wall at the top thereof and rearwardly extending lugs on the rear wall at the top thereof, vertical forwardly extending fins on the lower portion of the front wall, and vertical rearwardly extending fins on the lower portion of the rear wall.
7. In a traveling grate, the hollow transverse carrier-bar 44, comprising a one-piece casting having spaced front and rear walls connected by integral webs 46, laterally spaced front and rear lugs 49, at the top of the front and rear walls and integral therewith, strengthening ribs 45 integral with the front and rear walls, and vertical front and rear fins 48 below the said strengthening ribs and integral with the front and rear walls.

In testimony whereof I affix my signature in the presence of two subscribing witnesses.

JOHN VAN VLECK.
